R. E. SMITH

FILLING STATION

Filed Aug. 9, 1926

INVENTOR:
ROBERT E. SMITH
BY *Kenneth Hudson & Kent*
ATTORNEYS.

UNITED STATES PATENT OFFICE.

ROBERT E. SMITH, OF SOUTH EUCLID, OHIO.

DESIGN FOR A FILLING STATION.

Application filed August 9, 1926. Serial No. 18,661. Term of patent 14 years.

To all whom it may concern:

Be it known that I, ROBERT E. SMITH, a citizen of the United States, residing at South Euclid, in the county of Cuyahoga and State of Ohio, have invented a new, original, and ornamental Design for a Filling Station, of which the following is a

companying drawing, forming part thereof.

The figure is a perspective view of a filling station showing my new design.

I claim:

The ornamental design for a filling station substantially as shown.

ROBERT E. SMITH.
